(57) **CLAIM**

The ornamental design for a pasta making machine, as shown and described.

DESCRIPTION

FIG. 1 is a perspective view of a pasta making machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the pasta making machine.
The broken lines in the drawings depict portions of the pasta making machine that form no part of the claimed design.**1 Claim, 9 Drawing Sheets**FIG. 1

FIG. 2

FIG. 3

FIG. 4

FIG. 5

FIG. 6

FIG. 7

FIG. 8

FIG. 9
